NUT CRACKER

David Edmunds Davis, Box 253, Stratton, Colo.

Filed Dec. 27, 1960, Ser. No. 63,333

Term of patent 7 years

(Cl. D44—1)

Fig. 1

Fig. 2

Fig. 1 is a perspective view of a nut cracker, showing the rear and left side of my new design; and

Fig. 2 is a similar view showing the front and right side of my new design.

The portion of a typical nut is shown in broken line in both views for illustrative purposes only.

I claim:

The ornamental design for a nut cracker, as shown and described.
